VENTILATING RANGE HOOD

Samuel M. Bernstein, Winnetka, Ill.

Application March 14, 1956, Serial No. 571,499

4 Claims. (Cl. 98—115)

This invention relates to ventilating hoods and more particularly to the type of ventilating hoods frequently used in connection with kitchen cooking ranges. Specifically the invention relates to improvements in such hoods affording means for combining exhaust fans with the range and incorporating lighting means therein.

The use of ventilating hoods for collecting fumes to exhaust the same from an enclosure, has long been known. The use of such hoods in connection with cooking ranges in institutions and restaurants has likewise long been known. More recently, however, the use of such ventilating range hoods in individual private homes has become increasingly popular. Although such hoods may be used independently solely for the purpose of collecting cooking vapors, fumes and odors, it is obvious that their most efficient use is in combination with blower unit exhaust fans of the type illustrated in my co-pending application. Such a combination insures healthful ventilation and complete freedom from objectionable cooking odors, vapors, greases and the like.

From the foregoing, it is apparent that the combination of an exhaust fan with a ventilating range hood is most desirable. However, heretofore such combination has been accomplished haphazardly without pre-designed means for combining the two units. Hence, whenever it was desired to combine a ventilating range hood with an exhaust fan, it was usually necessary to employ a skilled electrician to individually effect a combination of the two units. Such a procedure was obviously quite expensive. Often in those instances where unskilled labor was employed to effect the combination, dangerously unsatisfactory wiring resulted.

Heretofore, however, even in those instances where a proper combination of the two units was accomplished, there was no provision made for convenient access to the fan controls. Likewise in view of the fact that by its very nature the hood often was so positioned as to shield the top of the range from natural lighting sources, it was often necessary to provide artificial lighting. This also required installation by skilled electricians. Without the provision of readily accessible light control means, access to the same was also a problem.

Since as stated above, those hoods are merely for the purpose of collecting fumes from the stove and expelling them through a stove pipe, attached to the hood, they need not be too sturdy. For that reason they are commonly made from a rather thin sheet material, usually metal. The hoods overlie the cooking stove or range, and consequently are rather large. This creates a problem, particularly at the front of the hood, because it is not easy to build a large reasonably rigid hood with a large expanse of unsupported thin sheet material. This problem is accentuated by the requirement that the hood be strong enough to support a plurality of appliances such as a light source and fan. One of the objects, therefore, of this invention is to reconcile the economic requirements for a hood made from thin sheet material which still possesses a desired amount of rigidity.

2

A further object is to afford a ventilating range hood designed for ready association with an exhaust fan unit.

Yet another object is to provide a ventilating range hood having built-in lighting means.

5 Yet a further object is to afford a ventilating range hood having control means for both the fan and the light mounted in readily accessible position and in full view, preferably in the foremost portion of the hood.

Still another object is to provide a ventilating range 10 hood having all of the electrical wiring connected therein so that all that need be done to complete the connection with an exhaust fan is to connect the proper wires of the ventilating range hood to the proper terminals of the fan unit. Similarly the range lighting unit is provided with

15 proper wiring enabling ready connection of the same to the customary building power source.

Still a further object is to afford a ventilating range hood which may be readily installed with the least possible effort and skill and requiring no special tools for such 20 installation.

Finally another important object is to provide a ventilating range hood of the type hereinabove described of simple, inexpensive construction, yet attractive, sturdy and most useful.

25 With the foregoing and other objects in view which will appear as the description proceeds, the invention consists of certain novel features of construction, arrangement and a combination of parts hereinafter fully described, illustrated in the accompanying drawings, and particularly

30 pointed out in the appended claims, it being understood that various changes in the form, proportion, size and minor details of the structure may be made without departing from the spirit or sacrificing any of the advantages of the invention.

35 For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the 45 drawings:

Fig. 1 is a perspective view of a ventilating range hood installation with portions of the walls broken away to illustrate certain details of construction;

Fig. 2 is a fragmentary front elevational view of a portion of the hood showing the control panel;

Fig. 3 is a similar fragmentary view with one of the elements removed to illustrate certain details of construction;

Fig. 4 is an enlarged fragmentary sectional view taken 55 on the plane of line 4—4 in Fig. 2 of the drawings and viewed in the direction indicated;

Fig. 5 is a fragmentary plan view as viewed from the bottom of the hood when the same is installed in operational position as in Fig. 1 of the drawings;

60 Fig. 6 is a fragmentary sectional detail view taken on the plane of line 6—6 in Fig. 4 of the drawings and viewed in the direction indicated; and

Fig. 7 is another fragmentary sectional detail view taken on the plane of line 7—7 in Fig. 6 of the drawings and 65 viewed in the direction indicated.

Referring now to Fig. 1 of the drawings, reference numeral 10 indicates generally a hood comprising a front wall member 14 and a straight back wall 28. The back wall is adapted to be secured to a fixed vertical wall 11.

70 The top edges of the front and back walls are connected by a top surface 12. This top surface includes a flat top wall 24 secured at one end to back wall 28 and at the other end

by means of flange 22 to an arcuately curved portion 20. The opposite end of this curved portion 20 is connected to a flat portion 18 which extends downwardly from the curved portion and outwardly with respect to the wall 11. The outer end of portion 18 is connected by means of a curved segment 16 to the front wall member 14.

This front wall member, as seen in Fig. 1, extends downwardly from the curved segment 16 and inwardly toward wall 11. End walls 26 are provided for the hood. The top and side edges of these end walls are secured to the front and rear walls, and the top surface of the hood. The bottom edges of the front wall member 14 and end walls 26 are inwardly curved to form U-shaped flanges 25, see Fig. 4. This has the effect of strengthening the hood and increasing its rigidity.

As shown in Fig. 1 of the drawings, the hood 10 is mounted above the range R so that smoke, fumes, odors, greases and the like rise in the direction indicated by the arrows and are collected by the hood. The top wall 24 of the hood may be provided with a cutout portion 30 into which may be fitted an exhaust fan unit (not shown). Such an exhaust fan unit draws in the collected vapors, fumes and the like and then discharges the same by means of suitable ducts (not shown) to the outside atmosphere.

An electric light and an electric exhaust fan unit are adapted to be mounted on the hood. The control units or switches 50, 50', 50" etc. for these appliances are mounted on a support plate 51 secured by stud screws 52 to the inside of a protective sealed housing, indicated generally as 32. The housing comprises a strip of sheet material, in this case metal, bent to form an enclosure defined by side walls 36, a back wall 38, and a front wall 40. A bottom wall 42 detachably connected to said housing forms a cover plate to permit access to the control switches inside the housing. As seen in Figs. 1 and 5, the cover plate 42 has upwardly extending flanges 43 which embrace the bottom portions of the walls of the housing. Screws 45 penetrate the flanges of the cover plate and the walls of the housing to removably secure them together.

As seen in Fig. 4, the front and top edges of the end walls 36 are shaped to conform to the cross section of a portion of the top surface 12 and front wall 14 of the hood. With this arrangement, when the enclosure is secured by means of screws 44 to that portion of the hood, the top surface and front wall of the hood, along with the enclosure walls forms the sealed housing 32. The housing is adapted to protect the control switches and other electrical appliances such as a transformer 54 and fused leads 56 and 68 mounted inside, from the corrosive effect of fumes and heat and in addition as an added function it strengthens the hood. This is because the housing acts as a brace between the top surface and front wall of the hood. It should, of course, be obvious that any suitable fastening means such as welding, riveting or the like may be used in lieu of the screws 44 to secure the enclosure to the hood.

In addition, the front wall 40 of the enclosure is coextensive with a substantial portion of the front wall 14 of the hood to further strengthen it. In the example shown, this portion is more than $\frac{1}{6}$ of the length of the hood, see Fig. 1. Since hoods of this type are generally formed of thin sheet material, usually metal, they need to be strengthened, particularly at their front region, and this structure provides this. An elongated aperture 46 (Fig. 3) is formed in the front wall 14 of the hood. Portions of the control switches 50, 50', 50", etc., project out of the housing 32 and through aperture 46. Push buttons 48 are connected to these portions of the control switches for actuating them (Figs. 2, 3 and 5). Power is supplied to the housing through leads 70 which extends into the housing at 74 through a protective hollow tube 72 (see Fig. 4).

A panel face plate such as 58 may be provided to cover the push button slot 46. The fact plate 58 may be provided with a plurality of individual openings such as 60 through which the push buttons 48 may protrude.

The housing 32 has still another function. It acts as a support for both the electric light 66 and the light reflector 76. As seen in Fig. 4, a bracket 62 is secured to the back wall of the housing 32. The electric light 66 and the light socket 64 are connected to the bracket. A conventional electric circuit (not shown) connects an electric power source to both the electric light and the electric exhaust fan through the control switches 50, 50', 50", etc.

For the purpose of increasing the lighting efficiency of the bulb 66, a novel removable reflector such as 76 may be provided. This reflector 76 may be formed from a strip of metal bent in the shape shown in Figs. 1, 4, 6 and 7 of the drawings to afford a flat top surface 78 with the inner protruding edge arcuately bent as at 80 and the outer ends sharply bent at an angle of 90° to afford a straight flange 82. The inner arcuately bent portion 80 helps to reflect the light forwardly to the area where it is most needed. The flat bent flange 82 may be formed with a pair of slots such as 84 therein. These slots 84 are adapted to cooperate with complementary offset tabs 86 in the housing back wall 38 to mount and retain the reflector in position on the housing 32.

From the drawings and foregoing description, it should be apparent that I have provided a novel highly utilitarian ventilating range hood having means for associating the same with an exhaust fan and having incorporated therein illuminating means adapted to effectively illuminate the top of the range which would otherwise be masked from both artificial or natural light sources. In using the same, the housewife need merely manipulate the push buttons of the switch as she stands in front of the range to control and regulate both the light and fan.

Eliminated entirely by my novel ventilating range hood are inconvenient, costly wall switch installations and dangerous, haphazard, oftentimes non-standard electrical circuits. By reason of the foregoing, groping for hidden, hard-to-reach, greasy switches is likewise eliminated.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. An apparatus of the class described comprising a ventilating range hood formed of thin sheet metal and including at least a top surface and a depending front wall, said hood adapted to have appliances mounted thereon, said appliances including illuminating and reflecting means, a housing having end walls, a rear wall, a bottom wall and a front wall, the front and top edges of said end and back walls shaped to conform to the cross section of a portion of the top surface and front wall of the hood, means securing the front wall of the housing to the front wall of said hood whereby the said portion of the top surface and the front wall of the hood are maintained in tight engagement with the upper edges of the end and rear walls of the housing, forming a sealed housing and reinforcing the top front portion of the hood, said hood portion having an aperture in the front wall thereof, control switches for said illuminating means mounted in said housing, push buttons operatively connected to the control switches for actuating the same, said push buttons projecting through the front wall of the housing and outwardly through the aperture in the front wall of the hood, a bracket mounted on another wall of the housing, said illuminating means mounted on said bracket for disposition within the hood adjacent the rear wall of the housing, the rear top region of the hood having another aperture through which the fumes from the range may pass, said reflecting means being mounted on the housing and positioned over the illuminating means.

nating means to direct the light from the illuminating means in the desired direction.

2. An apparatus of the character described in claim 1, wherein the rear wall of the housing is formed with a struck-out tab, the reflecting means comprising a strip, the inner end of which is bent to form a downwardly directed flange for removable engagement with the struck-out tab.

3. An apparatus of the character described in claim 1, wherein the bottom wall of the housing is removable.

4. An apparatus of the class described comprising a ventilating range hood formed of thin sheet material and including at least a top surface and a depending front wall, said hood adapted to have appliances mounted thereon, a housing having at least end walls, a rear wall, and a bottom wall, the front and top edges of said end walls shaped to conform to the cross section of a portion of the top surface and front wall of the hood, means securing the housing to the hood whereby the said portion of the top surface and front wall of the hood are 20

maintained in tight engagement with the upper edges of the end walls of the housing thereby closing off the housing and reinforcing the top surface and front wall of the hood, control switches adapted to be connected to said appliances mounted in said housing, means connected to said control switches for selectively actuating them, a bracket mounted on one wall of the housing adapted to support a further appliance for disposition within the hood, said hood having an aperture therein 10 through which the fumes from the range may pass.
